(57) **CLAIM**

The ornamental design for a display panel with graphical user interface as shown and described.

DESCRIPTION

The file of this patent contains a drawing executed in color. Copies of this patent with color drawing will be provided by the Office upon request and payment of the necessary fee. The FIGURE is a front view of a display panel with graphical user interface showing my new design. The broken lines in the drawing show a portion of the display panel with graphical user interface, and form no part of the claimed design.
